UNITED STATES PATENT OFFICE.

UROSH BALTICH, OF GARY, INDIANA.

TOY.

Application filed December 27, 1921, Serial No. 525,107. Renewed March 12, 1923.

To all whom it may concern:

Be it known that I, UROSH BALTICH, a citizen of the United States, and a resident of Gary, in the county of Lake and State of Indiana, have invented a new and useful Improvement in Toys, of which the following is a full, clear, and exact description.

My invention relates to improvements in toys, and it consists in the combinations, constructions and arrangements herein described and claimed.

An object of my invention is to provide a toy of the character described, in which an arrow may be projected into the air by the combined propulsion of the arm of the player and a resilient tension member.

A further object of my invention is to provide a toy of the character described, the parts of which may be placed side by side and the whole packed in a relatively small container.

A further object of my invention is to provide a device of the character described by means of which the skill of the player may be tried and developed.

Other objects and advantages will appear in the following specification, and the novel features of the invention will be particularly pointed out in the appended claims.

My invention is illustrated in the accompanying drawings, forming part of this application, in which—

Fig. 1 is a perspective view of an embodiment of my invention.

Fig. 2 is a plan view of one of the arrows, Fig. 3 is a side elevation of the arrow shown in Fig. 2,

Fig. 4 is a sectional view of the resilient tension member,

Fig. 5 is a modified form of an arrow tip, and

Fig. 6 is a modified form of the resilient tension member.

In carrying out my invention, I make use of a rod 1, at one end of which is an enlarged handle portion 2, by means of which the rod 1 will be supported in the hand 3. The opposite end of the rod 1 is provided with an enlarged head portion 4 which is substantially the same diameter as the handle 2.

The relative lengths of the rod 1 and the handle 2 are substantially shown in Fig. 1. The rod 1 is preferably of wood, lending lightness and strength to the rod.

A short cord 5 is secured at one end to the

head portion 4 and at its other end to a heavy rubber-band 6, as shown at 7. The opposite end of the rubber-band 6 has secured to it a second short cord 8, as shown at 9. The free end of the cord 8 is provided with a knot 10.

An arrow 11 of light wood and having a thin wooden vane 12 at one end thereof is provided with a notch 13 intermediate its length, which notch is arranged to receive the cord 8 adjacent the knot 10 so that the cord may not be withdrawn from the notch when pulled in a forward direction, i. e., away from the vane 12. The forward end of the arrow 11 is provided with a blunt point 14 so that no danger is incurred should the arrow fall on one standing nearby. The contour of the stem 15 of the arrow 11 is clearly shown in the two views of the arrow in Figures 2 and 3.

The means for securing the cords 5 and 8 to the opposite ends of the rubber-band 6 is clearly shown in Fig. 4. The cord 5 is arranged to pass entirely around a short wooden stick 16 and the rubber-band 6 is supported upon the upper surface of the stick 16, thus the cord 5 or 8 will not cut the band 6 when force is applied thereto. The rubber-band 6 is tied closely by a string 17 directly under each of the sticks 16.

From the foregoing description of the various parts of the device, the operation thereof may be readily understood. The rod 1 with its handle 2 and the several arrows 11 are all painted or otherwise colored in an attractive manner, such as shown in Fig. 1, in which colored rings 18 are painted concentric the members.

In using the device, the player grasps the handle 2 in the right hand 3. He grasps one of the arrows 11 in the left hand 19 by its vane portion 12, the cord 8, having been placed with the knot portion 10 in engagement with the notch 13. The left hand 19 is then drawn back into the side of the body and the right hand 3 is swung to the right so that the rubber-band 6 will be fully extended. The hand 19 is thereupon released from the arrow 11 and at the same time the right hand is forcibly moved to the right and up. This will cause the arrow 11 to be projected into the air by the combined propulsion of the rubber-band 6 and the arm of the player. The arrow 11 will rise point foremost into the air and when

the energy of propulsion has been expended, it will describe a curve and descend with its point 14 pointed downwardly.

In Fig. 5, I have shown a modified form 5 of the tip of the arrow 11, in which I employ a sharp pin 20 in place of the blunt tip 14. This point is for use when shooting the arrow toward a target or when the player is assured that the arrow in falling 10 will not strike any person thereabout. The pin 20 will of course enter soft wood or similar material and the arrow will remain in a fixed position until removed by the player.

15 In Fig. 6, I have shown a modified form of the resilient tension member, in which I employ a tension spring 21 preferably of a non-rusting metal, such as bronze or the like. The use of the spring 21 is precisely 20 the same as the rubber-band 6 and the cords 5 and 8 are tied directly to loops 22 at each end of the spring 21.

I claim:

1. A device of the character described 25 comprising a rod having an enlarged handle portion and an enlarged tip portion, said tip portion having an annular groove therein, a cord secured at one end in the groove and said tip, a second cord terminating 30 at one end in a knot, a resilient tension

member connected between the free ends of said cords and the opposite ends of said cords, an arrow having a vane, a notched portion intermediate the length of said arrow, said notched portion adapted to receive the knotted end of said cord. 35

2. In a device of the character described, a resilient tension member comprising a rubber band, and flat sticks, one disposed at each end of said band and arranged to 40 engage the inner surface of said band, and a cord having a loop portion arranged to encompass the end wall of said band and said flat stick, whereby said cord may bear directly upon the exposed surface of said 45 stick when the tension member is extended.

3. In a device of the character described, a resilient tension member comprising a rubber band, and flat sticks, one disposed at each end of said band and arranged to 50 engage the inner surface of said band, a cord having a loop portion arranged to encompass the end wall of said band and said flat stick, whereby said cord may bear directly upon the exposed surface of said 55 stick when the tension member is extended, and means for drawing the sides of said band closely together adjacent said sticks.

UROSH BALTICH.
